UNITED STATES PATENT OFFICE.

AUGUST TEN WINKEL, OF DENVER, COLORADO, ASSIGNOR, BY DIRECT AND MESNE ASSIGNMENTS, OF ONE-HALF TO STANLEY H. BISSELL, OF DENVER, COLORADO, DWIGHT BISSELL, OF REDWOOD FALLS, MINNESOTA, AND FLORENCE M. COTTON, OF MINNEAPOLIS, MINNESOTA.

CLASSIFYING OR SIZING APPARATUS.

SPECIFICATION forming part of Letters Patent No. 741,565, dated October 13, 1903.

Application filed August 25, 1902. Serial No. 121,012. (No model.)

To all whom it may concern:

Be it known that I, AUGUST TEN WINKEL, a citizen of the United States of America, residing at Denver, in the county of Arapahoe and State of Colorado, have invented certain new and useful Improvements in Classifying or Sizing Apparatus; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in sizing or classifying apparatus for use in connection with concentrating-tables; and it consists of the features, arrangements, and combinations hereinafter described and claimed, 20 all of which will be fully understood by reference to the accompanying drawings, in which is illustrated an embodiment thereof.

In the drawings, Figure 1 is a top or plan view of the apparatus, one of the screens being partly broken away. Fig. 2 is a side elevation of the same viewed in the direction of the arrow in Fig. 1. Fig. 3 is a section taken on the line 3 3, Fig. 1, the parts being shown on a larger scale. Fig. 4 is an end view looking in the direction of the arrow A in Fig. 1. Fig. 5 is a detail view of the screen shown on an enlarged scale.

The same reference characters indicate the same parts in all the views.

35 Let the numeral 5 designate a concentrating-table, which as shown in the drawings is of the Wilfley type, being provided with longitudinal riffles 5^a.

40 My improved apparatus is mounted at the feed-corner of the table and arranged to receive the pulp discharged from the feed-box 6. This apparatus will now be described in detail, though it must be understood that the details of construction as set forth in the 45 specification and drawings may be varied without departing from the spirit of the invention.

A bed-plate 7 is placed upon the riffles 5^a of

the table 5, and on top of this plate is laid a covering of linoleum 8. Above and engaging 50 the linoleum are longitudinal riffles 9 extending parallel with the table-riffles below. To a frame 12 are applied several sections of screen of varying mesh and designated A, B, and C, respectively, the section A being finest— 55 say one hundred mesh—the section B next in fineness—say sixty mesh—and the section C fifty mesh. These sections all lie in the same plane and are connected together by soldering or otherwise to form a smooth joint or union. 60 The sections A, B, and C lie in an inclined plane, the section A being uppermost, the section B next below, and the section C lowest. The frame 12 consists of parallel side strips 12^a and 12^c and end strips 12^d and 12^e. The side 65 strips, as shown in the drawings, engage the linoleum 8 on opposite sides of the riffles 9—that is to say, the strip 12^a is located above the uppermost riffle and the strip 12^c below the lowermost riffle 9. In this specification 70 it is assumed that the table 5 is laterally or transversely inclined, the edge where the feed-box is located being highest. This inclination is not illustrated in the drawings. The part 12^d of the frame engages the plate 7 75 at the head of the table, while the part 12^e is of less thickness, and the riffles 9 are recessed or grooved to receive it. The screen-sections A, B, and C rest on the riffles 9. The sections 80 B and C are provided with projections 16 extending above their upper surface. On top of the screen-section A are located broken riffles or projections 13, while near the lower edge of this screen is located a continuous riffle 14. Above the parts 13 and 14 and resting thereon is a screen-section D of coarser mesh than the section A beneath. For convenience I will assume that this section D is eighty mesh. The section D is also provided with projections 16 extending above the upper surface. The parts of the frame 12 adjacent the edges of the screen D are thickened or built up to support the screen part D, 90 as shown at 12^b.

When the apparatus is in use, the pulp 95 from the feed-box 6 passes first to the screen-

section D, through which the ore particles of eighty mesh and finer pass to the screen-section A below. The eighty-mesh particles being too coarse to pass through the one-hundred-mesh screen, gradually work down through the broken riffles or projections 13 to the continuous riffle 14, whence they work rearwardly or toward the left, referring to Figs. 1 and 2 of the drawings, being discharged from the one-hundred-mesh screen at a point E beyond the frame 12, while the particles of one hundred mesh and finer will pass through the section A and be discharged to the riffles 9 below and gradually work rearwardly to the riffles of the table 5. It is assumed for the purposes of this specification that the table has a movement calculated to carry the material thereon from the right toward the left, referring to Figs. 1 and 2 of the drawings. The material too coarse to pass through the eighty-mesh screen will move transversely downwardly to the section B of sixty mesh. All the material of sixty mesh and finer will pass through the screen B to the riffles 9 below and move gradually rearwardly to the riffles of the table 5, while the particles coarser than sixty mesh will pass transversely downwardly to the screen-section C. The particles of fifty mesh and finer will pass through the screen-section C to the riffles 9 and move rearwardly along the riffles 9 to the table 5, while the particles coarser than fifty mesh will pass over the lower bar of the frame 12 to the table 5 below my improved apparatus. Thus it will be seen that by virtue of my improvement the particles of ore are delivered to the table 5 classified according to size, the finest particles being delivered to the upper part of the transversely-inclined table and the other grades to the lower portions of the table in the order of their fineness, thus enabling the table to perform the concentrating function much more efficiently than could be done without classification or sizing.

The projections 13 and 16 break up the pulp and separate the ore particles, whereby a more accurate and efficient classification of said particles is obtained.

In Fig. 5 of the drawings is shown an enlarged view of the preferred form of screen fabric employed for all of the screen-sections. In this construction the screen is passed through rollers or pressed from opposite sides to cause the outer surface of the two sets of strands to occupy the same plane. These strands are designated in Fig. 5 by the numerals 3 and 4. This treatment of the screen increases its wearing life, since it reduces to a minimum the resistance which it offers to the movement of the ore particles thereon. This construction of screen is also more efficient in performing the ore classifying or sizing function.

It will be observed from an inspection of the drawings that the projections 16 of the screen-sections D, B, and C increase in num-

ber for a given surface area from the upper portion of the apparatus downwardly toward its lower discharge edge. This is because the agitation of the ore particles should be increased as the ore works transversely downwardly from the upper portion of the apparatus.

My improved sizing apparatus is provided with an upwardly-projecting flange 17 extending along the upper side and across a head end thereof.

Having thus described my invention, what I claim is—

1. A classifier or sizer comprising a shaking transversely-inclined riffled bed, provided with screen-sections varying in mesh, the finest-mesh section being placed uppermost on the bed, and the other sections below in the order of their fineness, the coarsest section being lowermost, the said screen-sections being all located in the same inclined plane.

2. A classifier or sizer comprising a transversely-inclined riffled bed, provided with screen-sections varying in mesh, the finest-mesh section being placed uppermost on the bed and the other sections below in the order of their fineness, the coarsest section being lowermost, the said sections being all located in the same inclined plane and provided with projections applied to the upper surface of the finest section, and a section coarser than the finest section, but finer than the other sections lying in the same plane with the finest section, the said coarser section being placed upon the said projections of the finest section, and a riffle placed on the finest section below its projections to direct the material to the riffles beyond the screen, substantially as described.

3. A classifier or sizer comprising a transversely-inclined riffled bed provided with screen-sections varying in mesh, the finest-mesh section being placed uppermost on the bed and the other sections below in the order of their fineness, the coarsest section being lowermost, the various screen-sections being provided with projections extending above their upper surface.

4. The combination with a transversely-inclined table provided with longitudinal riffles, of a riffled bed applied to the feed-corner of the table and provided with screen-sections of varying mesh, the finest-mesh section being uppermost thereon, the other sections being arranged below in the order of their fineness and in the same inclined plane, the coarsest section being lowermost, and all the sections being provided with projections extending above their upper surface.

5. The combination with a transversely-inclined table provided with longitudinal riffles, of a riffled bed applied to the feed corner of the table and provided with screen-sections of varying mesh, the finest-mesh section being uppermost thereon, the other sections being arranged below in the order of their fineness and in the same inclined plane, the

coarsest section being lowermost, all the sections being provided with projections extending above their upper surface, and another section of screen coarser than the finest screen 5 but finer than the other sections in the same plane as the finest section, the said coarser section being placed upon the projections of the finest section and being itself provided with projections extending above its upper 10 surface, and a riffle located on the finest section at the lower edge of the section above for the purpose set forth.

6. A classifier and sizer comprising a riffled bed and a plurality of superimposed screen- 15 sections located thereon, the various sections being provided with projections extending above their upper surface, and means for discharging the various grades of ore particles from the sections at different points, substantially as described.

7. A classifier and sizer comprising a trans- 20 versely - inclined riffled bed, provided with screen - sections varying in mesh, the finest-mesh section being placed uppermost on the

bed and the other sections below in the order 25 of their fineness, the coarsest section being lowermost, the screen fabric of the sections being pressed to cause the outer surface of the crossed strands, to lie in the same plane, substantially as described.

8. A classifier or sizer comprising a trans- 30 versely - inclined bed provided with screen- sections varying in mesh, the finest-mesh section being placed uppermost on the bed and the other sections below in the order of their 35 fineness, the coarsest section being lowermost, the said screen-sections being provided with projections extending above their upper sur- face, the number of projections for a given 40 surface area, increasing from the upper edge of the apparatus downwardly, substantially as described.

In testimony whereof I affix my signature in presence of two witnesses.

AUGUST TEN WINKEL.
